2 Sheets-Sheet 2

Technical drawing of a structural frame assembly labeled Fig. 3. The drawing shows a rectangular frame with various dimensions and labeled components. Key features include:

- Dimensions: 42 (top left), 28 (left side), 20 (left side), 16 (bottom left), 36 (bottom center), 38 (bottom center), 18 (bottom right), 44 (bottom right), 42 (bottom right), 50 (right side), 48 (right side), 30 (right side), 20 (right side), 58 (center left), 58 (center right), 40 (center top), 14 (top center), and 24 (top right).
- Components: The frame is supported by vertical legs and horizontal beams. A central horizontal beam is labeled 40. Two vertical legs on the left are labeled 20. A vertical leg on the right is labeled 30. A vertical support on the far right is labeled 48, 50, and 42.

Application August 18, 1950, Serial No. 180,199

3 Claims. (CL. 275—2)

1

This invention relates to improvements in aggregate spreaders.

An object of this invention is to provide an assembly at the open end of a conventional, standard truck body which serves the purpose of an end gate and an aggregate spreader, said device consisting of a case or housing having a discharge slot at one end thereof and a valve arranged to open and close said slot, together with a means for operating the valve which is located adjacent to a platform upon which a worker may stand.

Another object of this invention is to provide an assembly adapted for attachment to a standard truck body which takes the place of the conventional tailgate, whereby without serious modification of the standard truck body an aggregate spreader is constituted, said aggregate spreader being totally devoid of any type of driving connection with any other part of the vehicle and avoiding the necessity of using a separate and independent vehicle for spreading the aggregate on a road.

Other objects and features of importance will become apparent in following the description of the illustrated form of the invention.

In the drawings:

Figure 1 is a fragmentary elevational view of a truck body having the attachment applied thereto, the truck body and attachment being shown in the discharging condition in phantom;

Figure 2 is a back view of the attachment;

Figure 3 is a front view of the attachment;

Figure 4 is a top view of the attachment;

Figure 5 is an enlarged sectional view taken substantially on the line 5—5 of Figure 4 and in the direction of the arrows;

Figure 6 is a perspective view of a part of the valve for controlling the discharge of aggregate from the truck body; and

Figure 7 is an enlarged fragmentary sectional view substantially on the line 7—7 of Figure 2 and in the direction of the arrows.

The instant invention deals with improvements in the art of spreading aggregate on surfaces, such as freshly treated roads or roadbeds. It has been found that by omitting the tailgate of a standard truck body 10 and substituting a device to serve the purpose of the tailgate and a spreader for aggregate, material saving as to initial investment may be avoided, inasmuch as a separate vehicle for spreading the aggregate is not necessary and, moreover, the aggregate may be discharged due to the pull of gravity when the standard truck body is elevated at its forward end about the pivot shafts 12 as an axis.

2

The attachment consists of a case or housing generally indicated at 14 and is adapted to be arranged in the open rear end of the truck body 10 and held in place by means of the stay-bolts 16 and 18, respectively. These bolts have nuts at one end and are welded or otherwise rigidly fixed to the side posts 20 which form a part of the structural framing for the housing 14. A horizontal header 22 is fixed by suitable means, as welding, to the vertical posts and there is a cross member 24 welded in place above the header for strength of construction.

The case 14 includes a rear wall 26 made of metal paneling and side walls 28 and 30 which are also of paneling and which taper outwardly and rearwardly from the vertical posts 20. A bottom or bottom panel 32 is connected to the side walls 28 and 30 and is adapted to rest upon the bottom 34 of the standard truck body 10.

There is a slot 36 formed in the case along the lower rear edge portion thereof and this slot or outlet for the aggregate is strengthened by means of the angle framing 38 which is rigidly fixed to the bottom panel 32 and to the rear wall 26 near the slot 36. Other framing, such as the angle 40, for example, may be employed wherever it is found desirable to strengthen the assembly and construction.

A platform 42 is fixed to the housing or casing 14 by means of a gusset plate 44 which is welded or otherwise rigidly fixed to the casing. When the body 10 and attachment are in tipped rearward position (Figure 1), the platform is employed to accommodate an individual whose job is to operate a valve generally indicated at 46 for controlling the rate of flow of aggregate through the slot or outlet 36. Such control takes place by operation of a handle 48 which is fixed to a valve shaft 50, this shaft being journaled in suitable openings which are formed in hangers 54. The hangers are welded, brazed or otherwise fixed to the framing 38 around the outlet 36.

The valve 46 is made up of a plurality of smoothly curved valve plates (Figure 6) 58, each of which has a pair of arms 60 and 61 extending therefrom. At the outer ends of the arms there is a tube 62 through which the shaft 50 passes (Figure 7). There is an aligned pair of openings 64 in the tube 62 and an aligned pair of openings 66 in the shaft 50 through which a pin 68 is adapted to pass. This pin is attached by means of a chain 70 to an eye 72, said eye being rigidly fixed to the tube 62.

When it is desired to discharge a controlled quantity of aggregate, the loaded truck body is

lifted to the position shown in dotted lines in Figure 1. The operator of the device stands upon the platform 42 and manipulates the valve handle 48. This causes each of the valve plates 58 which are coupled with the shaft 50 by means of their pins 68 to be rotated. As noted from inspection of Figure 1 the valve plate assemblies may be made of any width, to wit, the wider assembly shown at the left side of Figure 4 and the shorter assemblies on the right side thereof. The selection of how many of these assemblies should be used is left within the prerogative of the foreman or the individual in charge of operations whereby, by selection of one or more valves to be used, the width of discharge may be selected.

Having described the invention, what is claimed as new is:

1. An attachment for a truck body to constitute a tailgate therefor, said attachment comprising an aggregate spreader which includes a housing located at the discharge end of the truck body, said housing having a discharge opening therein, a shaft mounted for rotation adjacent said discharge opening and on the exterior of said housing, a plurality of curved valve plates, each valve plate having a tube connected therewith, said tubes being mounted rotatively upon said shaft mounting said valve plates in sealing relationship with said discharge opening, coupling pins for selectively securing said tubes to said shaft, and an actuator connected with said shaft for rotating the same whereby upon rotation of said shaft said valve plates secured thereto are operated.

2. An attachment for a truck body to constitute a tailgate therefor, said attachment comprising an aggregate spreader which includes a housing having a discharge opening therein, a shaft mounted for rotation adjacent said discharge opening and on the exterior of said housing, a plurality of valve plates, each valve plate having a tube operatively connected therewith, said tubes being mounted rotatably upon said shaft, coupling pins attaching said tubes to said shaft, and an actuator connected with said shaft whereby upon rotation of said shaft said valve

plates are operated, said coupling pins being removably disposed in locking engagement with said tubes and said shaft so that a selected number of said valve plates may be rendered operative in response to rotation of said shaft, and at least two of said valve plates being of different size.

3. An attachment for a conventional rearwardly tiltable dump truck body to constitute a tailgate therefor; said attachment comprising an aggregate spreader including a housing adapted to be fixed at the discharge end of the truck body, said housing having a discharge opening therein along its lower rear edge portion, a shaft journaled for rotation on said housing exteriorly thereof, a plurality of valve plates, each of said valve plates having a tube rigid therewith, said tubes being rotatably mounted on said shaft and supporting said plates in end-to-end relation, coupling means for selectively securing tubes to said shaft, an actuator connected with said shaft for rotating the same so as to move the valve plates secured thereto between open and closed positions, and a platform rigid with said housing and extending therefrom at an angle to the plane of the bottom of the truck body so as to occupy a substantially horizontal position when the truck body with said attachment in place thereon is moved into its rearwardly tilted position, said platform being disposed adjacent said actuator, whereby an operator can stand upon said platform to operate said actuator and said coupling means.
